ELECTRICAL CONNECTOR

James D. Cunningham, South Pasadena, Calif., assignor, by mesne assignments, to The Deutsch Company, Electronics Components Division, Los Angeles, Calif., a corporation of California

Filed Apr. 15, 1960, Ser. No. 22,475
8 Claims. (Cl. 339—176)

This invention relates to electrical connectors and, more particularly, is concerned with a multiple contact connector having snap-in contacts.

The use of multiple contact connectors for connecting and disconnecting a large number of electrical circuits in aircraft, communications, and the like is well known. In the interest of saving space, the contacts are arranged in very close relationship and supported by a block of insulating material. Because it is difficult to solder or otherwise connect electrical leads to such closely spaced contacts, connectors have been devised in which the contacts snap into position. Thus the contacts can be first secured to the associated electrical lead before they are snapped into position in the insulating block of the connector.

In the past, the cost of manufacturing connectors having these snap-in contacts has been substantially greater than the cost of ordinary connectors in which the contacts are permanently molded into the insulating block. Not only have snap-in type connectors been considerably more costly heretofore, but they have not provided a snap-in contact which could be easily removed from the insulating block once the contact had been snapped into position. Generally, if removable at all, snap-in contacts could be removed only by disassembling the entire connector assembly.

By the present invention, an improved multiple contact connector is provided in which the contacts are snapped into position and securely held. The individual contacts can be removed by means of a simple tool and independently disassembled from the rest of the connector assembly. The present invention provides a connector which utilizes contacts which conform to military standards, which standards prescribe the exact shape and dimensions of the contacts.

In brief, the present invention provides a connector assembly including an insulating block having a plurality of holes for receiving contacts. Each hole is formed with a retainer member of spring material with a split sleeve portion and a plurality of integrally attached axially projecting spring fingers. The outer surface of the split sleeve portion has an annular recess which is arranged to engage the shoulders formed by the reduced diameter section of the bore to lock the retainer member in the insulator block. Each of the spring fingers is arranged to slope inwardly away from the sleeve portion with the outer ends of the fingers again flaring outwardly. A shoulder is formed where the spring fingers start to flare outwardly. A contact member is inserted in the retainer member and is provided with a first portion of diameter larger than the inside of the sleeve, and a reduced diameter portion for engaging the shoulder of the fingers.

For a more complete understanding of the invention, reference should be had to the accompanying drawings, wherein:

2

FIG. 1 is an enlarged sectional view of a portion of the connector showing the snap-in contact assembly for both the plug and receptacle;

FIG. 2 is a side elevational view, partly in section, of the retainer member;

FIG. 3 is an end view of the retainer member; and

FIG. 4 is a side elevational view showing the manner in which the snap-in contact is removed.

Referring to FIG. 1 in detail, the two halves of the connector include insulating blocks 10 and 12. These blocks may be mounted in metal jackets forming a receptacle and plug which are arranged to be threaded together in the manner of conventional connector design. The block 10 is provided with a plurality of openings or bores extending through the block, such as indicated at 14. The bore 14 includes a reduced diameter region 16 forming a pair of spaced shoulders 18 and 20 in the central region of the block.

A spring retainer member 22, preferably made of beryllium-copper, is positioned in each bore in the block 10, the retainer member being shown in detail in FIGS. 2 and 3. The spring retainer member is cylindrical in shape and includes a sleeve portion 24 having an internal opening or bore 26. The sleeve portion is split along one side by a slot 28. The outside surface of the sleeve portion 24 is provided with an annular groove 30, forming a pair of spaced shoulders 32 and 34. The end of the sleeve portion is beveled on the outer surface, as indicated at 36.

The balance of the spring retainer member may be considered as comprising two spring fingers 38 and 40 formed by two slits 41 and 42 located diametrically opposite each other. The slit 41 is coextensive with the slot 28, while the slit 42 terminates at the sleeve portion 24. The inner and outer surfaces of the spring fingers conform to the cylindrical cross-sectional shape of the sleeve portion. However, in the longitudinal direction, the inner surface of the spring members tapers away from the sleeve portion in an inwardly direction, the inwardly tapered portion being indicated at 44. The inwardly tapered portion ends abruptly in a shoulder 46. The inner surface formed by the spring fingers then tapers outwardly to the end of the fingers, the outwardly tapered portion being indicated at 48.

Referring again to FIG. 1, it will be seen that the spring retainer member 22 is positioned in the bore 14 by means of the annular groove 30 which engages the shoulders 18 and 20 formed by the reduced diameter section 16. By means of the tapered portion 36 of the spring retaining member, it can be guided through the reduced diameter portion 16 from the front face of the block 10. By virtue of the slot 28, the spring retaining member can be reduced in diameter sufficiently to pass through the reduced diameter section of the bore, the split sleeve portion springing outwardly when the reduced diameter portion 16 engages the annular groove 30.

After a retainer member is secured in position in each of the bores in the block 10, pin members such as indicated at 50 may be snapped into position from the back side of the block 10. Each pin member includes a solid cylindrical portion 52 having an integral collar 54. The cylindrical portion 52 is of such diameter that it slides into the bore 26 in the retainer member 22. The pin member further includes a tapered portion 56 which forms a shoulder 58. The tapered portion 56 and shoulder 58 are positioned such that when the collar 54 engages

one end of the retainer member 22, the shoulder 46 on the spring fingers engages the shoulder 58, thus securing the pin member in position. The tapered inner surfaces 44 of the spring fingers of the retainer member act as cam surfaces by means of which the pin member, when inserted through the retainer member 22, spreads the fingers until they snap back into position behind the shoulder 58.

The companion block 12 is similarly provided with a plurality of bores 60, each having reduced diameter section 62 by means of which a spring retainer member 64 is held in position in the bores. Socket members, such as indicated at 66, are snapped in position in the retaining member 64 in identical fashion to the pin member 50 described above. Normally the socket members are set below the surface of the front face of the block 12. Wire leads are secured to the back ends of both the pin member 50 and socket member 66 by soldering or crimping in conventional manner.

Removal of either a pin member 50 or a socket member 66 can be affected by a special tool in the manner shown in FIG. 4. The tool, indicated at 70, has a handle 72 and a long hollow shank 74 secured to the handle. The end of the shank is beveled, as indicated at 76. The hollow shank fits around the projecting pin 50 and engages the flaring inner surface 48 of the spring fingers 38 and 40. This spreads the fingers sufficiently to permit the shoulder 46 to clear the shoulder 58 on the pin member. The pin member 50 can then be withdrawn out of the back of the insulator block 10.

What is claimed is:

1. A snap-in electrical connector assembly comprising a block of insulating material having at least one circular bore extending through the block, a portion of the bore intermediate the ends being reduced in diameter, a retainer member of spring material including a split sleeve portion and a plurality of integrally attached axially projecting spring fingers, the outer surface of the split sleeve portion having an annular recess region, the retainer member being secured axially within the bore of the insulating block by the reduced diameter portion of the bore engaging the annular recess region on the outer surface of the split sleeve portion, each of the spring fingers having an inwardly sloping inner surface portion adjacent the sleeve portion and having an outwardly sloping inner surface portion adjacent the projecting end of the finger, each finger having a surface substantially perpendicular to the axis of the retainer defining a shoulder between the inwardly and outwardly sloping portions opening toward the projecting end of the finger, the ends of the fingers being disposed within the bore and spaced from the walls thereof, and a contact member insertable in the retainer member having a first portion of diameter larger than the inside diameter of the sleeve portion of the retainer member and a second portion adjacent the first portion of diameter less than the inside diameter of the sleeve portion of the retainer member, a shoulder between the first and second portions adapted to engage the end of the sleeve portion of the retainer member remote from the spring fingers within the bore, the second portion of the contact member being recessed in one region to provide a shoulder positioned to engage the shoulder formed on the inner surface of each of the spring fingers, whereby the spring fingers lock the contact member in inserted position in the retainer member to secure the contact member from axial movement relative to the retainer member, wherein the outwardly sloping inner surface portions of the spring fingers provide means for disengaging the finger shoulders from the shoulder of the contact member for removal of the contact member without removal of the retainer member from the bore.

2. A snap-in connector assembly comprising a block of insulating material having at least one circular bore extending through the block, a portion of the bore inter-

mediate the ends being reduced in diameter, a retainer member of spring material including a split sleeve portion and a plurality of projecting spring fingers, the outer surface of the split sleeve portion having an annular recess region, the retainer member being secured axially within the extent of the bore of the insulating block by the reduced diameter portion of the bore engaging the annular recess region on the outer surface of the split sleeve portion, each of the spring fingers having an outwardly sloping inner surface portion adjacent the projecting end of the finger, the fingers being disposed within the extent of the bore and spaced from the walls thereof, each finger having a shoulder opening toward the outwardly sloping surface portion and a contact member insertable in the retainer member having a first portion of diameter larger than the inside diameter of the sleeve portion of the retainer member, and a second portion adjacent the first portion of diameter less than the inside diameter of the sleeve portion of the retainer member, a shoulder between the first and second portions adapted to engage the end of the sleeve portion of the retainer member remote from the spring fingers, the second portion being recessed in one region to provide a shoulder positioned to engage the shoulder formed on the inner surface of each of the spring fingers, whereby the spring fingers lock the contact member in inserted position in the retainer member, and whereby the outwardly sloping inner surface portions of the spring fingers provide means for disengaging the finger shoulders from the contact member shoulder for removal of the contact member from the bore without removal of the retainer member from the bore.

3. A snap-in connector assembly comprising a block of insulating material having a plurality of circular bores extending through the block, a portion of each bore intermediate the ends being reduced in diameter, retainer members of spring material each including a split-sleeve portion and a plurality of projecting spring fingers, the outer surfaces of the split-sleeve portions having annular recess regions, the retainer members being secured axially within the insulating block by the reduced diameter portions of the bores engaging the annular recessed regions of the split-sleeve portions, each of the spring fingers having an inwardly sloping inner surface portion adjacent the sleeve portion and having an outwardly sloping inner surface portion adjacent the projecting end of the finger, each finger having a shoulder between the inwardly and outwardly sloping portions, and contact members insertable in the retainer members having first portions of a diameter larger than the inside diameters of the sleeve portions of the retainer members and second portions adjacent the first portions of diameter less than the inside diameters of the sleeve portions of the retainer members, a shoulder between the first and second portions of each contact adapted to engage the end of the sleeve portion of the corresponding retainer member remote from the spring fingers, the second portions of the contact members each being recessed in one region to provide a shoulder positioned to engage the shoulder formed on the inner surface of each of the spring fingers, wherein the retainer members are secured to the insulating block prior to insertion of the contact members into the retainers and the spring fingers lock the contact members in inserted position in the retainer members, but wherein the spring fingers provide surfaces for disengaging the finger shoulders from the recesses of the contact members for removal of the contacts from the retainers.

4. A snap-in electrical connector assembly comprising a unitary block of insulating material having a hole therethrough, a retainer member made of spring material positioned within the hole, the retainer member including a split sleeve portion having projection means substantially circumferentially thereof which split sleeve portion expands within the hole whereby the projection means en-

gage the block to secure the retainer axially of the hole, the retainer member further including a pair of cantilevered spring fingers projecting from the split sleeve portion, the spring fingers being spaced at a point adjacent the projecting ends thereof a distance smaller than the internal diameter of the sleeve portion, the spring fingers each having an outwardly flaring inner surface between said point and the projecting end, the projecting ends of the spring fingers being disposed within the hole and spaced from the walls thereof, and a contact member removably secured by the retainer member previously secured in the hole, the contact member extending through the sleeve portion and the spring fingers of the retainer member, the contact member having a reduced diameter portion engaged by the spring fingers at said point of minimum spacing for securing the contact member in position, the outwardly flaring inner surfaces of the fingers providing means for wedging the fingers apart and away from the contact member to disengage the fingers from the contact member for removal of the contact member from the hole separate from the retainer, the contact member being secured to an electrical conductor at a location spaced from the reduced diameter portion, the conductor extending from the connector at the end thereof opposite from the spring fingers.

5. A snap-in electrical connector assembly comprising a block of insulating material having a hole therethrough, the hole having a central reduced diameter portion to provide enlarged diameter recesses at opposite ends of the hole, a retainer member made of spring material positioned wholly within the hole, the retainer member including a split sleeve portion having longitudinal spaced apart projections exteriorly thereof, which sleeve portion expands within the reduced diameter portion of the hole whereby the projections extend into the recesses for securing the retainer axially of the hole by engaging the reduced diameter portion at opposite ends thereof, the retainer member further including at least a pair of cantilevered spring fingers projecting from the split sleeve portion into one of the recesses, the spring fingers being spaced apart at a point adjacent the projecting ends a distance smaller than the inner diameter of the sleeve portion, a shoulder formed in each finger at said point adjacent the projecting end, the shoulders opening to the free ends of the fingers, the fingers flaring outwardly to their ends from the shoulders, the flaring ends of the fingers being spaced from the walls of the recess, and a contact member removably secured by the retainer member from axial movement in the hole, the contact member extending through the sleeve portion and the spring fingers of the retainer member from the end of the retainer opposite from the spring fingers, the contact member having a reduced diameter portion engaged by the spring fingers at said point of minimum spacing for securing the contact member in position axially of the hole, the flaring portion of the spring fingers providing a means for wedging the fingers apart within the one recess for removing the contact member.

6. A snap-in electrical connector assembly comprising a block of insulating material having a hole therethrough, a retainer member made of spring material positioned within the hole, the retainer member including a split sleeve portion having projections extending exteriorly therefrom, the split sleeve portion expanding within the hole so that the projections engage the block to secure the retainer member from movement axially of the hole, the retainer member further including a pair of cantilevered spring fingers projecting from the split sleeve portion, the spring fingers being spaced apart from each other at a point adjacent the projecting ends a distance smaller than the inner diameter of the sleeve portion, the spring fingers defining opposed outwardly flaring surfaces between said point of minimum spacing and the cantilevered ends of the fingers, the cantilevered ends of the spring fingers being spaced from the walls of the hole,

and a contact member removably secured by the retainer member, the contact member extending through the sleeve portion and the spring fingers of the retainer member, the contact member having a reduced diameter portion engaged by the spring fingers at said point of minimum spacing for securing the contact member in position, the flaring surfaces of the spring fingers providing means for wedging the fingers apart for removing the contact member.

7. A snap-in connector assembly comprising a block of insulating material having a circular bore extending through the block, a portion of the bore intermediate the ends being reduced in diameter, a retainer member of spring material including a split-sleeve portion and a plurality of projecting spring fingers, the outer surface of the split-sleeve portion having an annular recess region, the retainer member being secured axially within the insulating block by the reduced diameter portion of the bore engaging the annular recessed region of the split-sleeve portion, each of the spring fingers having an inwardly sloping inner surface portion adjacent the sleeve portion and having an outwardly sloping inner surface portion adjacent the projecting end of the finger, each finger having a shoulder between the inwardly and outwardly sloping portions, and a contact member insertable in the retainer member having a first portion of diameter larger than the inside diameter of the sleeve portion of the retainer member and a second portion adjacent the first portion of diameter less than the inside diameter of the sleeve portion of the retainer member, a shoulder between the first and second portions of the contact adapted to engage the end of the sleeve portion of the retainer member remote from the spring fingers, the second portion of the contact member being recessed in one region to provide a shoulder positioned to engage the shoulder formed on the inner surface of the spring fingers, wherein the retainer member is secured to the insulating block prior to insertion of the contact member into the retainer and the spring fingers lock the contact member in inserted position in the retainer member, but wherein the spring fingers provide surfaces for disengaging the finger shoulders from the recess of the contact member for removal of the contact from the retainer.

8. A snap-in connector assembly comprising a block of insulating material having a circular bore extending through the block, a portion of the bore being reduced in diameter, a retainer member of spring material including a split-sleeve portion and a plurality of projecting spring fingers, the outer surface of the split-sleeve portion having an annular recess region, the retainer member being secured axially within the insulating block by the reduced diameter portion of the bore engaging the annular recessed region of the split-sleeve portion, each of the spring fingers having an inwardly sloping inner surface portion adjacent the sleeve portion and having an outwardly sloping inner surface portion adjacent the projecting end of the finger, each finger having a shoulder between the inwardly and outwardly sloping portions, and a contact member insertable in the retainer member having a first portion of diameter larger than the inside diameter of the sleeve portion of the retainer member and a second portion adjacent the first portion of diameter less than the inside diameter of the sleeve portion of the retainer member, a shoulder between the first and second portions of the contact adapted to engage the end of the sleeve portion of the retainer member remote from the spring fingers, the second portion of the contact member being recessed in one region to provide a shoulder positioned to engage the shoulder formed on the inner surface of the spring fingers, wherein the retainer member is secured to the insulating block prior to insertion of the contact member into the retainer and the spring fingers lock the contact member in inserted position in the retainer member, but wherein the spring fingers provide surfaces for disengaging the finger shoulders from the

recess of the contact member for removal of the contact from the retainer.
